W. HILDEBRAND

BOILER FEED WATER HEATER

Filed Aug. 26, 1921

Amherst, Massachusetts
William Hildebrand
By Cessna, Bryant & Washburn

UNITED STATES PATENT OFFICE.

WILHELM HILDEBRAND, OF BERLIN-LICHTENBERG, GERMANY, ASSIGNOR TO HANDEL
MAATCHAPPIJ H. ALBERT DE BARY & CO., OF AMSTERDAM, NETHERLANDS, A
DUTCH COMPANY.

BOILER-FEED WATER HEATER.

Application filed August 26, 1921. Serial No. 495,509.

(GRANTED UNDER THE PROVISIONS OF THE ACT OF MARCH 3, 1921, 41 STAT. L., 1313.)

To all whom it may concern:

Be it known that I, WILHELM HILDEBRAND, a German citizen, residing at Neue Bahnhofstrasse 9-17, Berlin-Lichtenberg, Germany, have invented certain new and useful Improvements in Boiler-Feed Water Heaters, of which the following is a specification, and for which I have filed applications in Germany Apr. 9, 1914; Holland 10 Jan. 18, 1915; Austria Apr. 29, 1915; Norway Dec. 13, 1915; Finland June 21, 1919; Belgium Aug. 3, 1920; Spain Mar. 22, 1920; Poland Mar. 16, 1921; Rumania Mar. 16, 1921; Hungary May 7, 1915; Switzerland 15 May 1, 1915; Italy Apr. 15, 1915; France May 21, 1915; Great Britain Apr. 15, 1915; Sweden Apr. 30, 1915, Jugoslavia.

This invention relates to boiler feed water preheaters such as are used for example, on locomotives, of the known kind in which a tube spacing plate or disc of a diameter less than that of the preheater shell or casing is supported by the water tubes themselves in the case of U-shaped tubes, or by a water 25 cap in the case of straight open tubes, so that the nest of tubes and their spacing plate, together with the water cap, if any, can be withdrawn longitudinally from the interior of the shell.

30 The object of the invention is to provide one or more guides or supporting members within the shell of the preheater which while not positively connected with the tube spacing plate will engage the said plate at 35 one or more points on its edge in such manner as to facilitate its being placed in the correct position in relation to the shell without removing the steam cap and will support the said plate when in operation without resistance to slight longitudinal movements thereof caused by lineal expansion and contraction of the tubes due to variations in temperature.

45 Further objects and advantages of the said invention will be understood from the following description thereof with reference to the accompanying drawings, in which—

50 Figure 1 represents in longitudinal section a boiler feed water heater exemplifying this invention,

Figure 2 is a plan of the same heater, partly in section.

Figure 3 is an end elevation of the same with the steam cap removed. 55

Figure 4 represents in longitudinal section one end of a heater having a different arrangement of tubes.

The reference letter *r* indicates the shell of the heater, having steam inlet and outlet 60 branches marked *s* and *t* respectively, *w* the water chamber, *h* the steam cap, *m m* the water tubes, which pass through the tube plate *a*, the main function of which tube plate is in the case of U-shaped tubes to 65 prevent the tubes from swinging when the locomotive is running, while in the case of straight open tubes as shown in Figure 4 the tube plate has also the function of shutting off from each other and from the body of 70 the preheater the compartments in the water cap *y* into which the tubes open. Ribs or guides *b* are secured to the shell *r* by rivets *c* and are rigid throughout the greater part of their length, but the part of 75 each rib *b* nearest the steam cap *h* is preferably made somewhat yielding and adjustable in regard to its pressure on the edges of the tube plate. For this purpose the cross section of each rib *b* is reduced at the 80 part *d* thereof so that the free end of the rib can be pressed inwardly towards the center line of the preheater by the action of a screw *f*. A bolt *g* passes freely through the extremity of the rib *b*, the head of this 85 bolt engaging the inner side of the said rib *b*, and the said bolt *g* being adjustable in regard to the shell of the preheater so as to limit the horizontal inward movement of the end of the rib while permitting free 90 horizontal outward movement thereof. The edges of the tube plate *a* have opposite recesses in which the ribs *b* register as shown in Figure 3.

In addition to or in substitution for the 95 ribs *b* one or more guides or supporting members *e* may be secured to the preheater shell adjacent the operative position of the tube plate to engage flattened or rectilinear portions *a'* of the perimeter of the tube plate *a* (see Figure 3). When the tube plate has been placed in position, the free 100

ends of the guides *c* can be tightened against these straight edges *a'* by means of the screws *f*.

When the nest of tubes with the plate *a* has to be removed from the preheater, the screws *f*, *f'* are loosened so that the withdrawal of the plate *a* and tubes can be readily effected. When inserting the nest of tubes the plate *a* is placed with its lateral recesses in register with the guide ribs *b* and slid into position with its straight edges *a'* against the guide member *e*, and the screws *f*, *f'* are then tightened.

The invention is not limited to the examples of construction herein described, as the improvements can be adapted to other constructional forms of feed water pre-heaters without departing from the scope of the invention.

20 What I claim and desire to secure by Letters Patent of the United States is:—

1. In a feed water preheater, a shell, a tube plate within said shell, a plurality of water tubes penetrating said plate, said plate and tubes being conjointly movable longitudinally in relation to said shell, and guide ribs secured to said shell longitudinally thereof, said guide ribs being adapted to maintain supporting contact with said plate during its longitudinal movement and in its operative position.

2. In a feed water preheater, a shell, a recessed tube plate within said shell, a plurality of water tubes penetrating said plate, said plate and tubes being conjointly insertible into and withdrawable from said shell in a longitudinal direction, and guide ribs secured to said shell and adapted to register in the recesses of said plate during such insertion and withdrawal.

3. In a feed water preheater, a shell, a tube plate within said shell, a plurality of water tubes penetrating said plate, said plate and tubes being conjointly movable longitudinally in relation to said shell, and guide ribs secured to said shell longitudinally thereof, said guide ribs having yielding ends and being adapted to maintain supporting contact with said plate during its longitudinal movement and in its operative position.

4. In a feed water preheater, a shell, a tube plate within said shell, a plurality of water tubes penetrating said plate, said plate and tubes being conjointly movable longitudinally in relation to said shell, and guide ribs secured to said shell longitudinally thereof, said guide ribs having yielding ends adapted to maintain supporting contact with said plate in its operative position, adjusting screws working through

said shell to regulate the pressure of said yielding ends on said plate, and adjusting bolts permitting outward movement of said yielding ends.

65

5. In a feed water preheater, a shell, a substantially circular tube plate having a portion of its perimeter of rectilineal form, a plurality of water tubes penetrating said plate, said plate and tubes being conjointly movable longitudinally in relation to said shell, and a yielding guide member secured within said shell and adapted to engage said rectilineal portion of said plate.

6. In a feed water preheater, a shell, a substantially circular tube plate having a portion of its perimeter of rectilineal form, a plurality of water tubes penetrating said plate, said plate and tubes being conjointly movable longitudinally in relation to said shell, a yielding guide member secured within said shell and adapted to engage said rectilineal portion of said plate, and a screw working through said shell to regulate the pressure of said yielding guide member on said plate.

7. In a feed water preheater, a shell, a tube plate within said shell, a plurality of water tubes penetrating said plate, said plate and tubes being conjointly movable longitudinally in relation to said shell, guide ribs secured to said shell longitudinally thereof, and adapted to guide and support said plate during its longitudinal movements as well as in its operative position, and adjustable yielding guide members also secured to said shell and spaced apart from said guide ribs, said adjustable guide members being also adapted to support said plate when in its operative position.

8. In a feed water preheater, a shell, a substantially circular tube plate having recesses at each side and straight edges at top and bottom, a plurality of longitudinal water tubes penetrating said plate, said plate and tubes being conjointly insertible into and withdrawable from said shell in a longitudinal direction, guide ribs secured within the sides of said shell and adapted to register in said recesses in said plate, said guide ribs having yielding ends and means for enabling such ends to be adjusted in relation to said plate, yielding guide members secured within the shell at the top and bottom thereof adjacent the operative location of the tube plate and adapted to engage said straight edges on said plate, and means for adjusting the pressure of said yielding guide members on said straight edges of said plate.

WILHELM HILDEBRAND.
